BELLY ROLLER AND SIDE SPLITTING
MACHINEFrederic J. Coad, St. Louis, Mo., assignor to Swift
and Company, Chicago, Ill., a corporation of
Illinois

Application October 10, 1931, Serial No. 568,021

10 Claims. (Cl. 146—81)

The invention relates to a belly roller and side splitting machine and is particularly concerned with the providing of such a machine with a guiding means or shoe along which a rolled belly moves and by which it is guided in a straight path as the rolled belly section is severed by a cutter of the machine.

The invention also relates to an attachment for a belly roller and side splitting machine.

10 The object of the present invention is to provide a simple, practical and efficient guide of strong, durable and comparatively inexpensive construction designed to be applied as an attachment to belly roller and side splitting machines 15 and adapted to avoid bowed bellies. When feeding hog sides to the belly roller and side splitting machine there has always been a tendency for the sides to shift causing the bellies to be narrow at one end and wide at the other end. The attachment of the present invention practically eliminates this condition.

With these and other objects in view, the invention consists in the construction and novel combination and arrangement of parts herein- 25 after described, illustrated in the accompanying drawings, and set forth in the claims hereto appended, it being understood that various changes in the form, proportion and minor details of construction, within the scope of the claims, may be 30 resorted to without departing from the spirit of the invention or sacrificing any of the advantages thereof.

In the drawings:—

Fig. 1 is a side elevation of a guide attachment 35 constructed in accordance with this invention.

Fig. 2 is a rear elevation of the same.

Fig. 3 is a horizontal sectional view on the line 3—3 of Fig. 1.

Fig. 4 is a similar view on the line 4—4 of Fig. 1.

40 Fig. 5 is a perspective view of the guide attachment.

Fig. 6 is a detail perspective view of the vertically movable rod and the tension spring.

Fig. 7 is a side elevation of a belly roller and 45 side splitting machine showing the guide attachment applied thereto.

Fig. 8 is a rear end elevation of the same.

Fig. 9 is a detail vertical sectional view on the line 9—9 of Fig. 8.

50 In the accompanying drawings in which is illustrated the preferred embodiment of the invention, the guide attachment is shown applied to a belly roller and side splitting machine comprising in its construction a supporting frame 1, 55 an inclined endless conveyor 2, spaced belly

rollers 3 and 4 and circular cutters 5 and 6. The endless conveyor may be of any desired construction and is provided at the rotary cutters with ways, grooves or spaces 7 to receive the lower portions of the rotary knives to enable the same to 60 pass entirely through the hog sides and to a point slightly beneath the supporting surface of the endless conveyor. The knife receiving grooves or spaces may be formed in any desired manner, as will be readily understood, and in 65 the accompanying drawings, the endless conveyor is shown as composed of central and side sections 8 and 9. The rotary knives may have either smooth or tooth cutting edges. The hog sides are so placed on the conveyor in advance 70 of the belly rollers that the belly part will be pressed by the belly rollers while the fat back extends along one side of the rollers and the rotary knife which separates the fat back from the belly. The rotary knives are located at opposite sides of the machine which is adapted to 75 roll and sever either right or left bellies.

In order to prevent the hog sides from shifting and causing the bellies to be cut narrow at one end and wide at the other, the machine is 80 equipped with guides 10 consisting of shoes designed in practice to be placed approximately two inches to the right and left to the circular knives, as clearly illustrated in Fig. 8 of the drawings.

85 Each shoe which is constructed of suitable metal extends longitudinally of the endless conveyor and consists of a front curved portion 11 and a rear straight guiding portion 12. The front portion extends forwardly and upwardly from the front end of the straight guiding portion 12 and presents a convex surface to a hog side to enable the same to readily pass beneath the shoe which is yieldably mounted and which is adapted to exert a yieldable pressure upon the hog sides. 95

The straight guiding portion 12 which constitutes the body of the guide consists of a flat oblong bar laterally inclined or slanted and presenting an inclined plane lower face to the belly portion of a hog side and yieldably engaging the 100 same and adapted to guide and hold the hog side while the fat back is being severed by the rotary knife whereby shifting of the hog side and the cutting of bellies with one end narrow and the other end wide are practically eliminated. The 105 lateral inclination or slant on the body or guiding portion of the shoe is controlled by a tension spring 13 which produces the same pressure on thick and thin sides and thereby practically eliminates the tendency of the hog sides to shift while 110

passing through the machine. When the shoe is not engaging a hog side it is approximately one and one half inches from the endless apron of the conveyor at one side and the space between the inclined lower surface of the straight guiding portion of the shoe and the said apron tapers down to approximately one inch at the other side of the shoe.

The front curved portion 11 is narrow and approximately the same width as the straight rear guiding portion. The outer or front end of the curved portion 11 is approximately vertical and the lower rear portion is slightly inclined at 14 where it is connected to the straight rear guiding portion. One of the side edges of the curved front portions is in flush relation with the adjacent side edge of the straight rear guiding portion at the said point of connection and the entire side edge of the shoe at such side of the same is in the same plane.

The tension spring which is of spiral formation is disposed on a vertically movable rod 15 arranged in a hollow or tubular guide 16 and having an upper threaded portion 17 and a lower enlarged portion 18 provided at the top with a circular head 19 forming a seat for the lower end of the tension spring 13. The enlarged lower portion 18 is forked or bifurcated to provide a longitudinal slot 20 for the reception of a vertical arm 21 integral with the shoe and rising from the same at the juncture of the front and rear portions 11 and 12 thereof. The arm 21 fits in the slot 20 abutting against the upper end wall thereof and is secured to the sides of the portion 18 by a bolt 23 or other fastening device whereby the shoe is rigidly connected with the vertically movable rod 15.

The hollow or tubular guide is preferably rectangular in cross section and consists of front, rear and side plates 24 welded together at the corners at 25, as clearly illustrated in Fig. 4 of the drawings, but the hollow or tubular guide may be of any other preferred construction as will be readily understood.

The side plates of the guide are provided at their lower ends with vertical slots 26 extending upwardly from the lower ends of the said plates and open at their lower ends to receive the arm 21 which extends laterally beyond the lower portion 18 of the rod 15 at both sides of the same to slide in the said slots 26 whereby the rod is free to slide vertically and is held against rotary movement in the guide 16. The upper ends of the side plates of the guide are bent outwardly at right angles to form laterally extending attaching flanges or portions 27 which are secured by bolts 28 or other suitable fastening devices to a horizontal metal bar 29 extending across the machine, as clearly illustrated in Fig. 8 of the drawings and having the opposite guides secured to it. The transverse guide connecting bar 29 is preferably arranged at and secured to the lower face of the cross bar 30 of the machine, but the guides may be mounted in any other desired manner. The cross bar is arranged upon and secured to vertical posts or standards 33 which carry the bearings for the shaft 32 of the rotary knives 5. The knives and the endless conveyor may be driven by any suitable means as will be readily understood. The rod 17 extends through the bar 29 and the cross bar 30 and is provided at its threaded portion with a nut 31 adapted to engage the bar 30 and forming a stop for limiting the downward movement of the shoe for holding the same above and out of contact with the endless conveyor. By adjusting the

screw the size of the normal space between the shoe and the conveyor, may be varied.

It will be noted that the upper strand of the inclined endless conveyor 2 provides a longitudinally and rearwardly moving table upon which a hog side is supported while the belly portion of the hog side is being roll pressed and flattened and while the fat back is being cut from the rest of the hog side. This table in transverse direction extends horizontally but in longitudinal direction it extends rearwardly with a slight upward inclination. The circular cutters 5 and 6 which are carried on the transversely extending shaft 32 therefor which is above the table may be considered as cutters operatively associated with the table and each as operating in a vertically and longitudinally extending plane.

The spaced belly rollers 3 and 4 may be considered as rotatable, each about a transversely extending axis, and as being arranged above the table so that the axis of the rollers are ahead of the axis of the transversely extending cutter carrying shaft and so as to cooperate with the table to roll press and flatten the belly portions of a hog side as the latter moves rearwardly to a cutter, as 5 or 6.

The guides 10, consists of shoes each of which comprises the front curved portions 11 and the rear straight guiding section or portion 12, are located so as to extend rearwardly in respect to the cutter, in fact as shown each guide 10 is provided in and by an attachment that includes the vertically extending tubular guide 16 that is located behind the cutter carrying shaft 32. The guides 10 are located rearwardly in respect to the pressing and flattening rollers 3 and 4. Each guide or shoe thereof is transversely spaced from the cutter to which it corresponds and is arranged so as to engage and guide in a straight line the belly portion of a hog side as it passes from the cutter and until the fat back is completely severed from the rest of the hog side during the straight guided movement in a rearward direction. Each guiding portion 12 of the guide 10 has the lateral inclination or slant previously mentioned, namely, on the under side of the guiding portion 12 a slant which in transverse direction is upwardly and outwardly or in other words toward the cutter with which the guide is cooperatively associated. The laterally inclined shoe functions in holding the belly up against the knife and in avoiding bowed backs and extra trimming on the belly after passing through the machine. From an inspection of Fig. 7 it will be noted that the forward curved end 11 of the shoe engages the flattened belly portion shortly after the cutting operation thereupon has started and from then on and until the cutting operation is completed the shoe engages the flattened belly portion to control its position and ensure a rearward guided movement in a straight line.

The two sets of belly rollers, knives and guides enable the machine to roll and split right and left bellies, as indicated in dotted lines in Fig. 8 of the drawings, and the hog sides will be guided by the shoes in a straight line and will be prevented from shifting on the endless conveyor. Also, the shoes will exert substantially a uniform pressure on both thin and thick shoulders.

What is claimed is:

1. In a belly rolling and side splitting machine having a longitudinally and rearwardly extending table, a cutter operable in a longitudinally extending plane, rollers revolvable about transversely extending axis and arranged to flatten

- the belly portion of the hog side as the latter is fed longitudinally to the cutter while supported on the table during the cutting of the flattened belly portion from the rest of the hog side, an attachment comprising a guiding shoe presenting a laterally inclined surface to the belly of a hog side and adapted to hold the same in proper position for cutting and guiding the hog side in a straight line until the cutting operation is completed. 5

2. In a belly rolling and side splitting machine having a longitudinally and rearwardly extending table, a cutter operable in a longitudinally extending plane, rollers revolvable about transversely extending axis and arranged to flatten the belly portion of the hog side as the latter is fed longitudinally to the cutter while supported on the table during the cutting of the flattened belly portion from the rest of the hog side, an attachment comprising a guiding shoe having a straight flat laterally inclined portion presenting a plane inclined lower face to the belly of a hog side and adapted to hold the same in proper position for cutting and guiding the hog side in a straight line until the cutting operation is completed. 10

3. In a belly rolling and side splitting machine having a longitudinally and rearwardly extending table, a cutter operable in a longitudinally extending plane, rollers revolvable about transversely extending axis and arranged to flatten the belly portion of the hog side as the latter is fed longitudinally to the cutter while supported on the table during the cutting of the flattened belly portion from the rest of the hog side, an attachment comprising a guiding shoe having a straight narrow laterally inclined portion presenting an inclined lower face to the belly of a hog side, said shoe being also provided at the front with a narrow upwardly curved portion presenting a convex surface to the hog sides to enable the same to pass readily beneath the shoe whereby the belly is guided by the shoe until the cutting operation is completed. 15

4. In a belly rolling and side splitting machine having a longitudinally and rearwardly extending table, a cutter operable in a longitudinally extending plane, rollers revolvable about transversely extending axis and arranged to flatten the belly portion of the hog side as the latter is fed longitudinally to the cutter while supported on the table during the cutting of the flattened belly portion from the rest of the hog side, an attachment comprising a guiding shoe presenting a laterally inclined surface to the belly of a hog side and adapted to hold the same in proper position for cutting and guiding the hog side in a straight line until the cutting operation is completed, and yieldable means for maintaining the guiding shoe in contact with the hog sides and for causing approximately the same pressure on both thin and thick sides. 20

5. In a belly rolling and side splitting machine having a longitudinally and rearwardly extending table, a cutter operable in a longitudinally extending plane, rollers revolvable about transversely extending axis and arranged to flatten the belly portion of the hog side as the latter is fed longitudinally to the cutter while supported on the table during the cutting of the flattened belly portion from the rest of the hog side, an attachment comprising a guiding shoe presenting a laterally inclined surface to the belly of a hog side and adapted to hold the same in proper position for cutting and guiding the hog side in a straight line until the cutting operation is completed, a vertically movable rod connected with the shoe, a hollow guide receiving the rod, and a tension spring housed within the hollow guide for causing the shoe to engage both thin and thick sides with approximately the same pressure. 25

6. In a belly rolling and side splitting machine having a longitudinally and rearwardly extending table, a cutter operable in a longitudinally extending plane, rollers revolvable about transversely extending axis and arranged to flatten the belly portion of the hog side as the latter is fed longitudinally to the cutter while supported on the table during the cutting of the flattened belly portion from the rest of the hog side, an attachment comprising a guiding shoe presenting a laterally inclined surface to the belly of a hog side and adapted to hold the same in proper position for cutting and guiding the hog side in a straight line until the cutting operation is completed, an arm rigid with and rising from the shoe, a hollow guide having opposite slots guiding the side portions of the said arm, and a spring housed within the guide for urging the shoe downwardly. 30

7. An attachment for belly roller and side splitting machines comprising a guiding shoe presenting a laterally inclined surface to the belly of a hog side and adapted to hold the same in proper position for cutting and guiding the hog side in a straight line, an arm rigid with and rising from the shoe, a hollow guide having opposite slots guiding the side portions of the said arm, a spring housed within the guide for urging the shoe downwardly, and a rod secured to the said arm and provided with means for limiting the downward movement of the shoe. 35

8. An attachment for belly roller and side splitting machines comprising a guiding shoe presenting a laterally inclined surface to the belly of a hog side and adapted to hold the same in proper position for cutting and guiding the hog side in a straight line, an arm rigid with and rising from the shoe, a hollow guide having opposite slots guiding the side portions of the said arm, a spring housed within the guide for urging the shoe downwardly, and a rod extending through the guide and receiving the spring and having an enlarged portion engaged by the spring and secured to the said arm, and means carried by the rod for limiting the downward movement of the rod. 40

9. A belly rolling and side splitting machine comprising in operative combination and arrangement, a longitudinally and rearwardly moving table, a transversely extending cutter conveying shaft, a cutter thereupon operating in a vertically and longitudinally extending plane, rollers revolv- 45

ing about transversely extending axis and arranged for roll pressing the belly portion of a hog side while the latter is being fed rearwardly by the table to the cutter during the cutting of the fat back from the rest of the hog side and a guiding shoe located in the rear of the rollers and in transversely spaced relationship in respect to the cutter and having a longitudinally extending guiding portion with the under side of which the belly has sliding engagement whereby the hog side is held in position for cutting and is guided in a straight line until the cutting operation is completed, the under side of the longitudinally extending guiding portion of the guiding shoe having a lateral inclination extending upwardly and toward the cutter with which the shoe is associated. 50

10. A belly rolling and side splitting machine comprising in operative combination and arrangement, a longitudinally and rearwardly moving table, a transversely extending cutter conveying shaft, a cutter thereupon operating in a vertically and longitudinally extending plane, rollers revolving about transversely extending axis and arranged for roll pressing the belly portion of a hog side while the latter is being fed rearwardly by the table to the cutter during the cutting of the fat back from the rest of the hog side and a guiding shoe located in the rear of the rollers and in transversely spaced relationship in respect to the cutter and having a longi-

15

tudinally extending guiding portion with the under side of which the belly has sliding engagement whereby the hog side is held in position for cutting and is guided in a straight line until the cutting operation is completed, said guiding shoe having a convex front curved portion and a straight longitudinally and rearwardly extending guiding portion which in cross section has an under side that extends upwardly towards the cutter with which the guiding shoe is associated, said guiding shoe being supported so as to allow vertical movement against yieldable pressing means.
